Inventor

Samuel Buchsbaum

By Max W. Zabel, Jr.

UNITED STATES PATENT OFFICE.

SAMUEL BUCHSBAUM, OF CHICAGO, ILLINOIS.

SWITCH.

1,222,355.

Specification of Letters Patent. Patented Apr. 10, 1917.

Application filed October 18, 1915. Serial No. 56,400.

To all whom it may concern:

Be it known that I, SAMUEL BUCHSBAUM, a citizen of the United States, residing at Chicago, in the county of Cook and State 5 of Illinois, have invented a certain new and useful Improvement in Switches, of which the following is a full, clear, concise, and exact description, reference being had to the accompanying drawings, forming a part of 10 this specification.

My invention relates to switches, and has for its object the provision of an improved device of this character in which automatically quick acting mechanism is used to 15 break the circuit.

It is the object of this invention to provide a novel form of mechanism to accomplish this quick acting movement with as few parts as possible.

I will describe my invention more specifically by reference to the accompanying drawing illustrating two forms of carrying out my invention, in which:

Figure 1 is a central section showing some 25 of the parts of my improved switch in elevation;

Fig. 2 is a section on line *a—a* of Fig. 1;

Fig. 3 is a detail of construction;

Fig. 4 is a perspective view of the extensible contact making element;

Fig. 5 is a view showing a modification, and

Fig. 6 is a detail of construction.

Referring more particularly to Figs. 1 35 and 2, I show a casing 1 within which the switch elements are contained, which casing is provided with an attachment strip 2 of the usual variety by means of which the casing may be fastened to the wall as is well 40 understood. A front plate 3 of the ordinary variety partly shown in Fig. 2 covers the structure, permitting the extension therethrough however of buttons 4, 5, as will be readily understood. These buttons 4, 5 also

45 project through the strip 2 and are movable in and out similarly to the buttons in switches of a similar nature. These buttons 4 and 5 have extension rods 6 and 7 which have their ends pivotally connected with the 50 insulated rocker arm 8. This rocker arm by means of the pin 9 is pivotally supported between the ends of the U-shaped frame 10, this frame being preferably secured to the strip 2. The rods 6 and 7 are as shown in 55 the drawing preferably mounted between the parts 11 and 12 which are composed of

insulating material and form the rocker arm

8. These members 11 and 12 are each apertured at 13 and 14 to receive the portions 15 of the extension rods 6 and 7, and form a 60 means whereby said rods are pivotally secured to said rocker arm. The rocker arm 8 is further provided with the cut-away portion 16 and abutments 17 and 18 formed at each of its ends to confine the movement of 65 the contact making element 19. The cutaway portion 16 forms a track or race, within which the contact closing element 19 operates to open or close said switch when either one or the other of the buttons 4 and 5 are operated. 70

An extensible member generally designated 20 is utilized, which has one of its ends seated against the strip 2 and carries at its opposite end the contact closing element 19. This extensible member is composed of two 75

relatively movable members 21 and 22, the member 21 being seated in the strip 2 and the member 22 carrying the contact element 19. These relatively movable members 21 and 22 may be held together in any suitable 80

manner. The means shown in the drawings whereby these elements are held comprises the fingers 23, 23, provided upon the member 21, these fingers being bent so that they embrace the member 22 and permit of a 85

sliding movement between the parts 21 and 22, when the contact member 19 is actuated along the track or race 16. The end of the member 21 which is seated against the plate 2 is preferably constructed with the forked 90

end 24 having the portions 25, 25, which are mounted and confined in the lateral recesses 26, 26, of the aperture 27 provided in the frame 10. This construction readily permits the end of the member 21 to project 95

through the aperture and to be seated against the plate 2 and at the same time forms a means whereby said member is held against displacement, also permitting of its being pivotally mounted against said strip 2. 100

The other slidable member 22 carries a means for closing the circuit between the two connecting springs 28 and 29 which are mounted in the casing 1 and form a means by which the conductor of the outside circuit may be brought to within the casing 1. The end of the member 22 remote from the member 21 is provided with an insulating block 30 upon which the contact making element 19 is mounted. This member 30 insulates the contact making element 19 from the members 21 and 22. This insulating block

105

110

30 is designed to be placed between the laterally projecting ends 31 and 32 of the contact making element 19 and is provided with the projections 33, 33 at its ends and the projections 34, 34 between its extremities, these latter projections in combination with the recesses 35, 35, and the projections 36^a and 36^a adjacent said recesses formed in the element 19, produce a means whereby said element 19 is held in its proper relation to the member 22.

It will be noted that the projections 33, 33 protrude slightly above and below the laterally projecting ends 31 and 32 of the member 19. The object of this construction is to decrease the spark which is ordinarily produced when contact is made or broken between the element 19 and the connecting springs 28 and 29. As will be evident, these projections 33, 33 enter between the springs 28 and 29 previous to the members 31 and 32, thereby promoting a more uniform make and break, and consequently reducing the spark.

25 To produce a quick make and break of the electrical connections when the rocker bar 8 is rotated, and to cause the member 19 to ride against said rocker bar, and also to insure the proper seating of the member 21 against the strip 2, a coiled spring 36 is utilized which re-acts between the opposite ends of the relatively movable members generally designated 20.

In Fig. 5, I show a modification in which 35 the device is shown applied to a pendant switch having a rocker bar operating plunger 37 which is provided with the reduced portion 38 intermediate its ends, the reduced portion being straddled by the forked end 40 of the member 39 which projects from the rocker arm 40. Thus when the plunger is operated the contact member 19 will open and close the circuit between the contact springs 41.

45 It will be evident from the foregoing description that when either of the buttons 4 or 5 is operated the rocker arm 8 will be inclined and as same is rocked back and forth the contact making element 19 will slide 50 back and forth in the cut-away portion 16 toward and away from the contact springs 28 and 29 depending upon which of the two buttons is actuated, thereby opening and closing the circuit between these elements.

55 Having thus described several forms of my invention, what I claim as new and desire to secure by Letters Patent is:

1. A device of the class described having a pair of contact making elements, one of 60 which is movable, a pair of relatively movable members, means provided upon one of said members whereby the other member may slide upon said first aforesaid member, one of said members being provided with a 65 contact making element, the other of said

relatively movable members abutting a stationary member, and a spring re-acting between the ends of the relatively movable members.

2. A device of the class described having 70 a swinging member, a pair of contact making elements, one of which is secured to said swinging member, one end of said swinging member abutting a stationary member, said member being longitudinally extensible. 75

3. A device of the class described having a pair of contact making elements, one of which is movable, a pair of swingingly mounted relatively movable members, one of said members having said contact making 80 element provided thereon, and the other of said relatively movable members abutting a stationary member.

4. A device of the class described having a pair of contact making elements, one of 85 which is movable, means for moving said last mentioned contact element toward and away from the other contact making element, said means including a rotatable member, a swinging member provided with said 90 contact making element extending between said rotatable member and a stationary member, one end of said member abutting said stationary member.

5. A device of the class described having a 95 pair of contact making elements, one of which is movable toward and away from the other contact making element, a pair of swingingly mounted relatively movable members, one of said members having a contact making element provided thereon, the other of said members abutting a stationary member, means securing said members together, and a spring re-acting between the 100 ends of said relatively movable members. 105

6. A switch structure having a contact element, a bodily movable contact element, a rocker bar and spring to control said movable element by snap action, a shifting bar carrying said contact element, an abutment, 110 said spring being confined between said abutment and said movable contact element, and swinging means for slidably carrying the free extremity of said bar.

7. A switch structure having a contact element, a bodily movable contact element, a rocker bar and spring to control said movable element by snap action, a shifting bar carrying said contact element, and swinging means for slidably carrying the free extremity of said bar. 115

8. In a device of the character described the combination with a casing of a bridge secured to said casing having downwardly extending arms at a right angle below said 125 bridge, guides provided in said casing for said arms, a contact moving bar pivoted to said arms, a movable contact therefor, a spring adapted with said bar to control said contact, an arm associated with said contact, 130

and a swinging support for said arm mounted upon said bridge.

9. A device of the character described having a switch element, a movable switch element, a rocking bar to control said movable switch element along which said movable switch element is movable, means to define the limit of movement of said movable switch element, resilient means to hold said movable switch element in association with said rocking bar, and a pivotally mounted telescoping rocking link having its free end associated with said movable switch element. 20
10. A device of the character described having a switch element, a cylindrical movable switch element, a rocking bar to control 25
15. A device of the character described having a switch element, a cylindrical movable switch element, a rocking bar to control

said movable switch element along which said movable switch element rolls, means to define the limit of movement of said movable switch element, resilient means to hold 20 said movable switch element in association with said rocking bar, and a pivotally mounted telescoping rocking link having its free end associated with said movable switch element.

In witness whereof, I hereunto subscribe my name this 15th day of October, A. D., 1915.

SAMUEL BUCHSBAUM.
